UNITED STATES PATENT OFFICE.

ALLEN GARDINER INGALLS, OF LAPRAIRIE, QUEBEC, CANADA, ASSIGNOR OF ONE-HALF TO CHARLES MACKAY COTTON, OF MONTREAL, QUEBEC, CANADA.

CAN.

1,098,444.

Specification of Letters Patent. Patented June 2, 1914.

Application filed March 17, 1913. Serial No. 754,859.

To all whom it may concern:

Be it known that I, ALLEN GARDINER INGALLS, a subject of the King of Great Britain, and resident of Laprairie, in the Province of Quebec, in the Dominion of Canada, have invented certain new and useful Improvements in Cans; and I do hereby declare that the following is a full, clear, and exact description of the same.

10 The invention relates to improvements in cans and particularly those cans which are opened by the removal of a continuous strip around the side or end walls.

15 The invention consists essentially in the novel formation of the wall at the tearing strip portion, whereby the metal is upset in a way to avoid the destruction of the continuity of the strip formed by the weakening lines.

20 The objects of the invention are to obviate the necessity of applying ordinary can openers to cans opened by a key engaging a weakened part of the wall, to devise a simple reinforcement that will not increase the cost 25 of forming the tearing strip and generally to provide a can easy to open and therefore of little trouble to consumers.

25 In the drawings, Figure 1 is a perspective view of a can showing the tearing strip formed on the side wall. Fig. 2 is a perspective view of a blank showing one form of the invention. Fig. 3 is an enlarged cross sectional view showing another form of the invention. Fig. 4 is a perspective detail of 35 a portion of the can wall particularly showing the buttresses against V-shaped weakening lines.

30 Like numerals of reference indicate corresponding parts in each figure.

40 The difficulties experienced in various kinds of cans, which are opened by winding a strip from the wall around a key, have made that means of opening far less generally applicable, than is the case where the 45 strip, will without fail continue rolling around the key until the finish, in place of tearing across part way, as it does so frequently in the hands of inexperienced persons or even experienced persons, consequently this invention has to do with so forming the metal of the can where the strip occurs that reinforcement is provided which directs the line of tear to the weakening lines.

55 Referring to the drawings, 1 is the side

wall of the can having the tearing strip 2 terminating in the tongue 3 at the seam of the tin.

4 are V-shaped dents made in the metal of the wall, said dents forming the weakening lines.

5 are the buttresses formed against the inner walls of the V's and 6 are the buttresses formed against the outer walls of the V's, said buttresses being formed by a roller 65 having transverse teeth meeting the roller forming said dents and when applied close enough forming transverse indents 7, though the pressure may be such as not to leave the indents 7, merely upsetting the metal at the 70 rise of the V walls, so as to turn said metal up into a buttress 5 or 6.

In Fig. 3, a flat transverse surface is shown interrupted by a plurality of longitudinal dents 4.

75 In Fig. 2, the indents 7 are shown, and extend beyond the tearing strip at each side into the main portions of the can wall.

It will now be seen that the tearing strip is flanged on each side by a dent made in 80 the metal.

This dent as a rule is V-shaped, though any kind of a dent may be made and this invention is not limited to a V-shaped dent, nor is it limited to a peculiar way of upsetting the metal for the main feature is to work the metal between or beyond the outer weakening lines, so that the strip between said outer weakening lines shall not tear across during the act of opening and this is 90 shown by upsetting the metal in such a way that the reinforcement directs the parting or tearing of the metal.

95 The buttresses are of course an extremely important feature in this invention and the simple manner, in which they are made, has much to do with the value of the invention, as they cause no more difficulty in their formation than the ordinary method of making weakening lines, but they do effect a great 100 reinforcement, for they act as their name implies namely as a buttress, at each side of the weakening lines, thereby directing the tear to the peak of the V, or in the case of other methods of forming the weakening 105 lines directing the tear to the line between the outer end and inner buttresses.

In the case of several of the weakening lines being formed each line is of course buttressed and while the tendency is for line 110

of the tear to remain at the outer weakening lines always, the others are provided as a further security, for no matter how careless the operation of, opening may be it can never go through all of them.

What I claim is:

1. A can having in one of its walls impressions, longitudinal and transverse, said impressions creating at their intersections piled up metal on the sides of the longitudinal impressions.
2. A can having in one of its walls continuous V-shaped impressions forming

parallel guiding lines for a tearing strip completely around the can and transverse 15 impressions extending between and into said impressions, said wall at the intersections of said impressions having protuberances formed by the piling up of the metal against the slope of the V's.

20

Signed at the city of Montreal, Quebec, Canada, this tenth day of March, 1913.

ALLEN GARDINER INGALLS.
